UNITED STATES PATENT OFFICE

GEORGE W. BINNS, OF CINCINNATI, OHIO, ASSIGNOR TO CINCINNATI GRINDERS INCORPORATED, OF CINCINNATI, OHIO, A CORPORATION OF OHIO

HOPPER FEED

Application filed June 4, 1929. Serial No. 368,261.

- This invention relates to improvements in grinding machinery and more particularly to a mechanism for selective supplying of work pieces thereto.
- One of the principal objects of the present invention is the provision of an improved selector mechanism especially adapted for use in pre-positioning work pieces of headed or irregular form for automatic introduction thereof within the throat of a centerless grinding machine.
- A further object of the invention is the provision of a mechanism for use in conjunction with an automatic grinding machine which will satisfactorily sort out irregular shaped pieces from a hopper and properly select the end thereof, which will be presented for entrance into the grinding throat of the machine.
- Other objects and advantages of the present invention should be readily apparent by reference to the following specification, considered in conjunction with the accompanying drawings, and it is to be understood that I may make any modifications in the specific structural details hereinafter disclosed, within the scope of the appended claims, without departing from or exceeding the spirit of the invention.
- Figure 1 is a fragmentary perspective view of a portion of a grinding machine with the improved selector mechanism applied thereto.
- Figure 2 is an enlarged side elevation of the mechanism.
- Figure 3 is a front view thereof.
- Figure 4 is a fragmentary sectional view on the line 4—4 of Figure 2.
- Figure 5 is a section on line 5—5 of Figure 3.
- In the drawings, the numeral 10 designates the bed of a centerless grinding machine having thereon the wheel head 11 supporting a grinding wheel and the regulating wheel unit 12 supporting an opposed regulating wheel of a standard centerless grinder, it being understood that these parts, together, provide a work receiving throat.
- The present invention has been illustrated 50 as utilized in connection with the grinding
- of tapered articles 13, such as rollers for anti-friction bearings. These, in their rough form as in the finished condition, have a smaller diameter at one end than at the other and it is essential in automatic performance 55 of the grinding operation that the smaller end be presented to the grinding throat, in order that they may be suitably, axially introduced between the wheels for proper stock removal therefrom.
- To facilitate the introduction of the work, there is mounted upon the bed 10 a control unit 14, including a drive motor 15 and a shaft 16 operated thereby. Shaft 16 is provided with an eccentric 17, coupled by link 18 with an arm 19 on rock shaft 20, which controls the functioning of the present mechanism.
- Rising from the unit 14 is a bracket 21, bearing a suitable hopper 22 for reception of 70 work pieces 13. This hopper has a discharge throat, as at 23, with a depending collar 24, in which is slidably mounted the agitator tube 25 riding on the inner feed tube 26 carried by bracket 21. Reciprocation of 75 member 25 is effected through collar 27, coupled as by pins 29 with rock arm 28 on shaft 20. The operation of these parts should be clear by reference to Figure 2, in which it will be noted that as link 18 is shifted by eccentric 17, shaft 20 will be rocked and tube 25 moved from a position below the discharge throat 23 of the hopper to a position within 80 the hopper, serving to agitate the work pieces therein so that by gravity they will roll or move downward into the hopper and through 85 tubes 25 and 26.
- Tube 26 has a laterally curving portion 30, terminating at table 31 near the base of bracket 21. Table 31 has a discharge aperture at 32 and a communicating work receiving groove or slot 33, the slot being of less width than the greater diameter of the work piece. As a result, when a work piece is laterally disposed on the shelf to overlie 90 the slot it would tend to fit downward in the slot and the restriction is such that the major portion of the work piece may swing downward into the slot, being just supported at the upper or larger end thereof so that the suc-

cessive tapered work pieces are thereby automatically positioned to drop the smaller end first through the feed tube 34. To facilitate adjustment of the width of the slot, use may be made of an adjustable lateral guide plate 35, as shown in Figure 4.

Control of movement of the work pieces from tube 30 across table 31 and longitudinally of slot 33 is effected through the following described mechanism.

Coupled with collar 27 is a link 36 having its other end pivoted to rock arm 37 having a T head 38. This lever is intermediately pivoted as at 39 with lug 40 on bracket 21, 15 one of its cam ends engaging arm 42 of pusher 43 and the opposed cam portion of head 38 engaging lug 44 on rock arm 45, coupled to shaft 46 with pusher 47. An interponent spring 48 couples members 42 and 45 20 and serves as a joint means for resiliently urging both of said arms into engagement with the cam head 38. Relative pivotal mounting of the two parts is such that as tube 25 is raised, head 38 will urge pusher 43 25 into retracted position and at the same time will cause a low spot thereon to engage lug 44 so that spring 48 will be effective to shift pusher 47, laterally urging a work piece 13 into alignment with slot 33. As this is a 30 resilient urge, the work piece may be positively moved into direct alignment with the slot and serve as the limit of oscillation in this direction of the pusher 47. When collar 27 and link 36 are shifted in a reverse direction, the head 38 will positively retract pusher 47 and at the same time spring 48 will cause arm 42 to follow the contour of head 38, allowing pusher 43 to resiliently shift the work piece longitudinally of the slot until 35 it overlies the discharge or feed tube 32.

It will thus be noted that the two pusher members 43 and 47 are resiliently, alternately actuated into engagement with the work piece so that the work pieces are successively 45 shifted from tube to slot and slot to feed tube, the member 47 in conjunction with adjustable guide 50 limiting introduction of work pieces to one at a time, while the table itself is preferably disposed at an angle, as indicated in Figure 2, so that the work pieces will not roll into the slot but must be positively actuated in the direction thereof and there is no liability of jamming of a work piece behind pusher 43 in its advanced position.

From the foregoing description, considered in conjunction with the accompanying drawings, you will see there has been provided a simple and efficient co-operative 60 mechanism permitting of loose introduction of work pieces in a hopper combined with an agitator to stir up the pieces and cause them to tend to be discharged by gravity from the hopper, coupled with a selector mechanism 65 operated by the agitator for successively im-

parting step by step advance to individual work pieces and for automatically determining the position of the work pieces during said automatic advance, so that all will be properly presented to the machine for the grinding operation.

What is claimed is:

1. The combination with a centerless grinder of a feed mechanism therefor including a hopper, a discharge member for the hopper, an agitator movable within the hopper, a discharge line from the hopper, and means in the discharge line for automatically determining the manner of eventual discharge of pieces therefrom. 70

2. The combination with a centerless grinder of a feed mechanism therefor including a hopper, a discharge member for the hopper, an agitator movable within the hopper, a discharge line from the hopper, means in the discharge line for automatically determining the manner of eventual discharge of pieces therefrom, and operative connections between the agitator and selector mechanisms for effecting joint operation thereof. 80

3. A selector mechanism for a tapered roll grinder or the like, including a pair of feed tubes, means for transferring individual work pieces from one to the other of said tubes, and means intermediate the tubes for insuring initial presentation of the smaller diameter of the article to the entrance of the second tube. 90

4. A selector mechanism of the character described, including spaced feed and discharge lines, means for alternately shifting an individual work piece along angularly related branches of a feed path from one to another of said mechanisms, and means for retarding advance of a selected portion of the individual work piece in the path to insure predetermined manner of entrance of the work piece into the discharge tube. 100

5. A selector mechanism of the nature disclosed, including a hopper, a discharge tube for the hopper, a spaced work receiving tube, a table at the terminus of the discharge tube, means for laterally shifting a work piece on the table, a restricted slot adjacent the table, and means for transversely shifting a work piece along the slot whereby inter-engagement of the walls of the slot and the work piece will automatically determine the manner of presentation of the work piece to the work receiving tube. 110

6. A selector mechanism of the nature disclosed, including a hopper, a discharge tube for the hopper, a spaced work receiving tube, a table at the terminus of the discharge tube, means for laterally shifting a work piece on the table, a restricted slot adjacent the table, means for transversely shifting a work piece along the slot whereby inter-engagement of the walls of the slot and the work piece will automatically determine the manner of pres- 125

entation of the work piece to the work receiving tube, and means for effecting alternate operation of the shifter mechanism.

7. A selector mechanism of the nature disclosed, including a hopper, a discharge tube for the hopper, a spaced work receiving tube, a table at the terminus of the discharge tube, means for laterally shifting a work piece on the table, a restricted slot adjacent the table, means for transversely shifting a work piece along the slot whereby inter-engagement of the walls of the slot and the work piece will automatically determine the manner of presentation of the work piece to the work receiving tube, and means for individually, resiliently actuating the shifter mechanism in an operative direction.

8. A selector mechanism of the nature disclosed, including a hopper, discharge tube for the hopper, a spaced work receiving tube, a table at the terminus of the discharge tube, means for laterally shifting a work piece on the table, a restricted slot adjacent the table, means for transversely shifting a work piece along the slot whereby inter-engagement of the walls of the slot and the work piece will automatically determine the manner of presentation of the work piece to the work receiving tube, means for individually, resiliently actuating the shifter mechanism in an operative direction, and a single means for alternately moving said members into inoperative position.

9. In a device of the class described the combination of a hopper, means for conveying work from the hopper, a work receiving table at the end of the conveying means, work positioning means adjacent the table, a pusher for transferring the work from the table to the positioning means, a conveyor operatively associated with the positioning means, and a second pusher for discharging the work from the positioning means into the conveyor.

- 45 10. In a device of the class described the combination of a hopper, means for conveying work from the hopper, a work receiving table at the end of the conveying means, work positioning means adjacent the table, a pusher transferring the work from the table to the positioning means, a conveyor operatively associated with the positioning means, a second pusher for discharging the work from the positioning means into the conveyor, and means synchronizing the movement of the pushers whereby the work is actuated across the table to the positioning means ahead of the second pusher.

- 60 11. In a device of the class described the combination of a hopper, means for conveying work pieces from said hopper in a continuous stream, a work receiving table at the terminus of said conveying means, work positioning means adjacent the table comprising an adjustable member movable relative

to the table and forming a work receiving slot therewith, and means for successively placing work pieces in said positioning slot and discharging the said work therefrom.

- 70 12. In a device of the class described the combination of a hopper, means for conveying work pieces from said hopper in a continuous stream, a work receiving table at the terminus of said conveying means, work positioning means adjacent the table comprising an adjustable member movable relative to the table and forming a work receiving slot therewith, means for successively placing work pieces in said positioning slot and discharging the said work therefrom, and means locking said adjustable member and table relative to one another whereby work of different sizes may be accommodated.

In testimony whereof I affix my signature.
